UNITED STATES PATENT OFFICE.

LARS GRONDAHL, OF RED WING, MINNESOTA.

WASHING-MACHINE.

SPECIFICATION forming part of Letters Patent No. 505,981, dated October 3, 1893.

Application filed October 20, 1892. Serial No. 449,482. (No model.)

To all whom it may concern:

Be it known that I, LARS GRONDAHL, a citizen of the United States, residing at Red Wing, in the county of Goodhue, State of Minnesota, have invented certain new and useful Improvements in Washing-Machines, of which the following is a specification, reference being had therein to the accompanying drawings.

10 My invention is designed to produce a neat and compact machine adapted to operate on large and small washings without undue wear on the clothes, during the operation of washing, and when not in use, to be transformed into a piece of furniture resembling an upright refrigerator, and is an improvement on the washing machine for which a patent was granted to me February 23, 1892, No. 469,402.

The improvement relates to the means for 20 fastening down and releasing the pounders frame, the means for elevating the pounders frame and retaining it at any desired elevation, and the means for dividing the interior of the tank into two compartments.

25 In the accompanying drawings, Figure 1 is a longitudinal vertical section of a washing machine constructed in accordance with my invention. Fig. 2 is a transverse vertical section of the same on line $z-z$ of Fig. 1. Fig. 3 30 represents on a larger scale a horizontal section of a portion of the stationary and movable frames adjacent to the bearings of the main shaft, and a portion of said shaft in top view. Fig. 4 is a vertical section on line $y-y$ of Fig. 1 of the lower portion of the stationary and movable frames and the means for elevating the latter frame. Fig. 5 is a perspective of a portion of the upper part of the tank. Fig. 6 is a perspective view of the dividing plate for said tank.

40 In said drawings A represents the end uprights of the frame, which are resting upon and are secured to the sills A², and the latter are united together by the bottom boards A³. 45 The two rear uprights are united together by the rear boards A⁴ of the frame. The front and rear uprights are united in pairs by boards A⁵ secured to their inner face, and are grooved vertically down the sides facing each other, and thus the uprights furnish parallel guides for the vertically movable side pieces B of the frame carrying the pounders C. The

side pieces B are united together at the top, by the stationary rear half D of the cover and at the rear by the horizontal strips B², which are bolted to the strips B' attached to the inside of the pieces B. Said strips B² serve, also, as rear supports and guides for the vertical stems C² of the pounders, a lateral movement of said stems being prevented by cleats b secured to the strips B² in front of said stems. The pounder stems are vertically slotted to make room for the cranks on the crank shaft E, which has its bearings in horizontal blocks B³ secured to the inner side of the side pieces B. One end of said shaft extends through one of the pieces B and is provided with a crank-handle e having a socket to engage with said shaft, but removable therefrom. Between the crank-handle and the side B, a ratchet-wheel e² is secured upon the shaft, and a pawl e³ is pivoted to the side B below the ratchet-wheel to engage with the latter and prevent the shaft from rotating, and the sides B with their pounders from descending after they have been elevated to permit the removal of the tank F. Upon the opposite end of the shaft E, a fly-wheel E² is mounted, that may be used as a belt-wheel. Each crank of the shaft E is united to a pounder by means of a connecting rod C³ having one end received in a cavity of said pounder and pivoted thereto at c. The front face of each pounder, is provided with horizontal serrations or inverted steps, which are to press upon the clothes placed with suds in the tank F, and partly revolve them under each pounding, and to facilitate and obtain this rotation the concave bottom of the tank is made semi-cylindrical in continuation of its vertical walls.

To facilitate the removal of the tank from the machine when the clothes and suds are to be placed therein, or removed therefrom, small wheels f are mounted upon short axles 95 and retained in cavities formed in blocks f' secured to the bottom of the tank.

To permit the removal of the tank, the front A⁶ of the machine is hinged to the bottom board A³ and is adapted to be tipped down 100 and make a floor level with the top of the board A³.

To facilitate the attachment of a wringer to the tank, which is preferably of tinned

- sheet metal, a narrow board f^2 , is attached to said tank along one of its edges. The tank may be divided into two or more compartments with one or more pounders to operate therein, either to reduce the size of the tank or permit clothes of different textures to be operated upon separately. For this purpose, a tinned sheet metal plate F^2 is placed vertically across the tank and its form corresponds with the interior thereof. The edges F^3 of said plate are bent and coiled around a wire to give thereto the required stiffness and its upper edge is coiled around a wire F^4 , the front end of which is bent to form a hook to enter one of the perforations f^3 in the upper edge and front of the board f^2 , while its rear end is kept straight and is made to rest on the rear edge of the tank between the pounders.
- 20 To cause the lower end of the plate F^2 to resist the pressure of the clothes subjected to the pounders in one of the compartments, a rod F^5 of suitable length is attached to said plate near the bottom thereof by a hooked toe piece F^6 passed under and in the rear of a strap F^7 secured to the side of the plate F^2 , the opposite end of the rod bearing against the end of the tank. A rod of suitable length is to be used according to the location given 30 the plate F^2 in the tank.
- 25 To elevate the frame B, carrying the pounders to permit the removal of the tank, a strap g of leather or other suitable material has one end secured at g^2 to the back of each upright and passes through a slot in said upright to the front side thereof, where it descends back of the frame B, passes around a pulley h mounted in said frame and through a slot b^2 therein, to a sleeve e^4 to which the 35 opposite end of the strap is secured. Said sleeve (one for each end of the shaft,) is mounted loosely upon the shaft, and has an under cut or dovetailed groove e^5 lengthwise thereof, in which is placed a bolt e^6 having 40 its sides correspondingly beveled. To keep said bolt from escaping out of the ends of the grooves e^5 , it is longitudinally slotted, and through the slot thus formed, a pin e^7 is secured to the sleeve. The bolt has also a small 45 knob e^8 on one end, by which it can be moved endwise by the operator when he desires to clutch the sleeve e^4 to a collar k that is fast on the shaft E. Said collar k has a V shaped groove k^2 in its periphery, one arm of said V being parallel with the axis of the shaft, while 50 the other arm is inclined to said axis.
- 55 When it is desired by the operator to elevate the frame carrying the pounders (after having released it from the stationary frame 60 as will be hereinafter described,) the bolts e^6 are pushed into engagement with the groove k^2 as shown on the left hand half of Fig. 3, and the handle e is rotated in the direction taken by the hands of a clock, until the pounders are sufficiently elevated to remove the tank. The pawl e^3 is then placed in engage-

ment with the ratchet wheel e^2 which retains the parts stationary. When it is desired to lower the frame B, the handle e is grasped and the pawl e^3 removed from engagement 70 with the ratchet wheel, and the handle is revolved in an inverse direction, and with it the shaft E and its V grooved collar k . The inclined face of said groove causes the bolt e^6 to be pushed back within the groove e^5 to the 75 position shown on the right hand half of Fig. 3, so that when the frame B has reached the bottom of its course, the shaft E is free to be rotated in either direction desired, to operate the pounders. 80

To prevent the frame B from being pushed up by the pounders striking the clothes in the tank, said frame is locked down to the inner boards A^5 of the stationary frame by means of screw rods m , each having a T head 85 at the lower end thereof, and pivoted to said board A^5 . The upper end of each bolt enters a groove in the front end of the strips B^4 of the movable frame, and a thumb nut on said rod is made to bear upon said strips. 90

The upper part of the machine is closed by the cover D^2 , hinged to the rear portion D thereof, and by the front panel D^3 hinged to the part D^2 of the cover.

Having now fully described my invention, 95 I claim—

1. The combination of a washing-machine frame having uprights at the corners, a frame B adapted to slide between said uprights, a crank shaft, a grooved collar secured to said 100 shaft, a sleeve loosely mounted upon said shaft, a longitudinally movable bolt to engage with the collar, and a strap having one end secured to the sleeve and the other end to one of the posts, with a guide pulley carried by 105 the frame B, substantially as described.

2. The combination of a washing-machine frame having uprights at the corners, a vertically movable frame between said uprights, a crank shaft, a collar secured to said shaft 110 and having a groove with divergent sides in its surface, a sleeve loosely mounted on said shaft, a movable bolt retained by said sleeve, a strap having one end secured to the sleeve and the other end to one of the posts, and a guide 115 pulley carried by the movable frame, substantially as described.

3. The combination of a washing-machine frame having uprights at the corners, a vertically movable frame between said uprights, 120 a crank shaft, a clutch member secured to said shaft, a sleeve loosely mounted upon said shaft and carrying another clutch member, a strap having one end secured to the sleeve and the other end to one of the posts, and a 125 guide pulley carried by the movable frame, substantially as described.

4. The combination of a washing machine frame having uprights at the corners, a vertically movable frame between said uprights, 130 a crank shaft, a ratchet wheel thereon, a pawl to engage with said wheel, a clutch mechan-

ism upon said crank shaft and having one member carried by a sleeve, a strap having one end secured to the sleeve and the other to one of the posts and a guide pulley carried by the movable frame, substantially as described.

5. The combination of a washing-machine frame having uprights at the corners, boards A⁵ uniting said uprights, a vertically movable frame between said uprights, a crank shaft and vertically reciprocating pounders carried by the movable frame, and means substantially as described for elevating the movable frame, with bolts *m* pivoted to the boards A⁵ and having projections on their

upper end in engagement with the movable frame, substantially as described.

6. In a washing machine a tank having a board f² secured thereto and perforation f³ in said board, a removable dividing plate in 20 said tank having a hooked rod in its upper edge, and a brace rod F⁵ secured to its side substantially as described.

In testimony whereof I affix my signature in presence of two witnesses.
